UNITED STATES PATENT OFFICE.

FRANK JOSEPH RIHA, KNOWN AS DON RIHA, OF CHICAGO, ILLINOIS.

DESIGN FOR AN ARTIFICIAL TREE.

Application filed August 31, 1927 Serial No. 23,252. Term of patent 3½ years.

To all whom it may concern:

Be it known that I, FRANK JOSEPH RIHA (known as DON RIHA), a citizen of the United States, residing at Chicago, in the county of Cook and State of Illinois, have invented a new, original, and ornamental Design for an Artificial Tree, of which the following is a specification, reference being had to the accompanying drawing, forming a part thereof.

Fig. 1 is a view in elevation of an ornamental artificial tree made of such material as colored translucent glass showing my new design of artificial tree; and

Fig. 2 is a bottom plan view.

I claim:

The ornamental design for an artificial tree, as shown and described.

FRANK JOSEPH RIHA.
